(57) **CLAIM**

The ornamental design for a portable gaming monitor, as shown and described.

DESCRIPTION

FIG. 1 is a front-top-right perspective view of a portable gaming monitor showing our new design.

FIG. 2 is a rear-bottom-right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left-side elevational view thereof; and,

FIG. 8 is a right-side elevational view thereof.

The dashed broken lines in the drawings show portions of the portable gaming monitor that form no part of the claimed design.

1 Claim, 6 Drawing Sheets
